UNITED STATES PATENT OFFICE.

MORRIS D. FLETCHER, OF SPRINGFIELD, MASSACHUSETTS.

TWINE-HOLDER.

1,122,716.

Specification of Letters Patent. Patented Dec. 29, 1914.

Application filed August 4, 1913. Serial No. 732,809.

To all whom it may concern:

Be it known that I, MORRIS D. FLETCHER, a citizen of the United States of America, residing at Springfield, in the county of 5 Hampden and State of Massachusetts, have invented a new and useful Twine-Holder, of which the following is a specification.

My invention relates to improvements in devices for gripping and holding cord, 10 string, or twine, the latter term being hereinafter employed to designate whatever my device is capable of receiving and acting upon, and said invention consists essentially of a certain peculiar receiver provided with 15 a resilient gripping and releasing element for the twine, all as hereinafter set forth. The device is also provided preferably with a twine-cutter.

The primary object of my invention is to 20 provide a simple, inexpensive, convenient, and efficient device which is capable of holding twine in such a manner as at all times to cause to be presented in readiness for instant use the free end of the twine, and to 25 permit said twine to be drawn freely through the holder, the resilient gripping and releasing means operating automatically to prevent the twine from slipping or being drawn through the holder in the wrong direction, without interfering in any way with 30 the twine when drawn through the holder in the right direction.

A further object is to provide such a device or holder with convenient means for 35 introducing the twine therein or for "threading" the same.

Still another object is to equip said holder with a suitable twine cutter, whereby the twine after being drawn through the holder 40 in the desired amount may be readily and conveniently severed.

I attain these objects by the means illustrated in the accompanying drawings, in which—

45 Figure 1 is a front elevation of a practical form of my invention; Fig. 2, a side elevation of the same; Fig. 3, a side elevation of the holder, showing the cover-plate swung open, and, Fig. 4, a similar elevation to 50 those shown in the two preceding views except that the cover plate is here omitted.

Similar figures refer to similar parts throughout the several views.

The holder as herein illustrated comprises 55 a bracket which is designed to be fastened by means of screws against a wall or under

a counter in convenient relationship or adjacency to a holder for a ball of twine, and such bracket consists of flanges 1—1, which are the screw-receiving parts, and a receiver 60 2 on opposite sides of which at one end said flanges are located. The receiver 2 is provided with a spring 3, and has a cover plate 4 pivotally attached thereto at 5. Formed in the receiver 2 is a longitudinal passage or 65 groove 6 for the twine, a short length of which latter appears at 7 in the first three views. Leading from the groove 6 intermediate of its ends and forming an acute angle therewith is a passage or groove 8. The 70 spring 3 is curved or bent at one terminal, as shown at 9 in Fig. 4, and said spring is received in the groove or recess 8, and is of such length and so arranged that its free terminal projects across the groove 6 and 75 bears against the wall thereof which is adjacent but opposite to the open end of said recess, or against the twine 7 when the same is present in said groove 6.

By constructing and arranging the holder 80 and spring as above set forth, provision is made for retaining said spring in place through the medium of its own resiliency, and said spring becomes a most efficient medium for gripping the twine in such a 85 way that it can be drawn through the groove 6 in one direction only.

The plate 4 is designed to cover the grooves 6 and 8, when said plate is in its closed position, in which position the plate 90 is retained by means of a stud 10 set therein and an indentation 11 in the adjacent face of the receiver 2. The plate 4 is provided with a twine cutter 12 which is an extension from said plate in the form of a 95 hook. The cutter 12 extends from that portion of the plate 4 which is contiguous to the pivot 5. When the plate 4 is closed one edge thereof contacts with or abuts one of the flanges 1 so that a rigid structure for cutting purposes is afforded, in view of the fact that the cutter 12 projects beyond the pivot 5 and has its cutting edge at the back or adjacent to said flange, it being observed that said pivot is located 100 near what would be one corner and that an outer one of the device if the same were not curved in its side profile.

In practice, the holder is threaded by opening the plate 4 and introducing the 110 twine 7 into the groove 6, slipping said twine between the end of the spring 3

which is in said groove and the rear wall of the groove. Now it will be readily seen that the twine 7 can be drawn upwardly through the groove 6 without hindrance on the part 5 of the spring 3, since the latter, owing to its inclination upwardly and rearwardly, yields for the passage of the twine, but that any tendency of the twine to drop down through said groove, or any attempt to draw 10 the same downward, must be instantly checked, owing to the firm grip which said spring normally exerts on the twine and which is greatly increased by force applied to the twine below the spring.

15 It is customary to draw off whatever length of twine may be required for a given purpose and then to sever the same on the cutter 12, the plate 4 being, of course, normally closed so as to present said cutter in 20 operative position.

Although I have shown the holder in a vertical position, it is clear that it can be used with equal facility when in a horizontal or any other suitable position.

25 What I claim as my invention, and desire to secure by Letters Patent, is—
1. A twine-holder comprising a member having therein a groove that extends therethrough, and a second groove that opens 30 at one end into the first intermediate of the ends of the latter, and a spring in said second groove and extending into said first-mentioned groove, said spring being in acute-angular relation to the wall of said

first-mentioned groove which is opposite to 35 that through which said second-mentioned groove opens.

2. The combination, in a twine-holder, with a receiver having a twine-groove therein, and also having therein a recess opening 40 into said groove, of a spring receivable in said recess and projecting into said groove, said spring having a bent terminal portion adapted forcibly to engage the sides of 45 said recess to retain said spring in place.

3. The combination, in a twine-holder, with a receiver having a twine-groove therein, and provided with a resilient member which projects into said groove, of a cover-plate attached to said receiver over said 50 groove, and provided with a twine-cutter.

4. The combination, in a twine-holder, with a receiver having therein a twine-groove, and provided with a resilient member which projects into said groove, and a 55 flange projecting from said receiver, of a cover plate pivotally attached to said receiver over said groove, and provided with a twine-cutter, the parts being so arranged that pressure on said cutter in the act of 60 severing the twine is counteracted by said flange which is in the path of said plate when the latter is in its closed position.

MORRIS D. FLETCHER.
